(57) **CLAIM**

The ornamental design for a male member of a connector, as shown and described.

DESCRIPTION

FIG. 1 is a front view of a male member of a connector showing my new design, the rear view thereof being identical to the front view;

FIG. 2 is a right side view thereof, the left side view thereof being identical to the right side view;

FIG. 3 is a top plan view thereof;

FIG. 4 is a bottom plan view thereof;

FIG. 5 is a cross sectional view taken along line 5—5 in FIG. 3; and,

FIG. 6 is a cross sectional view taken along line 6—6 in FIG. 3.
